UNITED STATES PATENT OFFICE.

ROBERT K. DAWSON, OF AKRON, NEW YORK.

FITTING FOR CHAIRS OR THE LIKE.

Application filed April 7, 1924. Serial No. 704,624.

To all whom it may concern:

Be it known that I, ROBERT K. DAWSON, a subject of the King of Great Britain, residing at Akron, in the county of Erie and 5 State of New York, have invented a new and useful Improvement in Fittings for Chairs or the like, of which the following is a specification.

This invention relates to fittings for chairs 10 or analogous articles which are adapted to support the seat of the chair on the usual spindle, and also to support the back of the chair, if one is used.

The objects of this invention are to provide a fitting of this kind with a seat-supporting member or spider of improved construction; also to provide means of improved construction for mounting a tilting or swinging back on a chair; also to provide spring 20 means of improved construction for opposing the tilting of the chair back; also to provide improved means for mounting the chair back on the chair fitting; also to provide means of improved construction for adjusting 25 the angle of the chair back with reference to the seat; also to improve the construction of fittings for chairs of this kind in other respects hereinafter specified.

In the accompanying drawings:

30 Fig. 1 is a top plan view of a chair fitting embodying my invention.

Fig. 2 is a fragmentary sectional elevation thereof on line 2—2, Fig. 1.

Fig. 3 is a perspective view of a pivot 35 member of the back tilting mechanism.

Fig. 4 is a rear view of the adjusting member of the back tilting mechanism.

Fig. 5 is a longitudinal, central, sectional elevation of a chair fitting embodying my 40 invention, showing a chair seat applied thereto, and also a part of a chair back arranged in operative relation thereto.

Fig. 6 is a transverse sectional elevation 45 thereof on an enlarged scale on line 6—6, Fig. 5.

Fig. 7 is a fragmentary perspective view showing the connection between the two cross members of the seat-supporting spider.

Fig. 8 is a perspective view of the adjusting member to which the lower end of the 50 back post of the chair is secured.

Fig. 9 is a fragmentary sectional elevation on an enlarged scale on line 9—9, Fig. 1.

Fig. 10 is a fragmentary sectional elevation 55 on an enlarged scale on line 10—10, Fig. 4.

The invention is shown in the accompanying drawings as embodied in a fitting adapted for use in connection with typewriter chairs, but it will be obvious that 60 parts of my invention may be used in connection with chairs of other kinds.

The seat-supporting spider of my improved chair fitting includes a pair of cross members A and B, which in the preferred 65 embodiment of the invention shown in the drawings, are substantially of channel or U-shaped cross section. The sides or flanges of the transversely extending member A extend downwardly, and the sides or flanges 70 of the forwardly and rearwardly extending member B extend upwardly, and at the intersection of these two channel-shaped cross members, they are provided with holes arranged in vertical alinement through 75 which the upper end of the screw stem or spindle C of the chair extends, this upper part c being preferably of reduced diameter, thus forming a shoulder against which the cross member B rests, and the upper portion 80 of the reduced part c of the stem or spindle C is preferably upset or riveted over against the horizontal face of the other cross member A so that the two cross members are securely held in engagement with each other 85 by means of the spindle C. The outer ends of the cross members A and B are secured to the seat D in any suitable or usual means, these cross members being so bent that the ends thereof extend upwardly above the intersecting middle portion.

In order to hold the two cross members securely in fixed relation to each other and at the same time to bring the horizontal faces thereof as closely together as possible 90 without materially weakening the vertical flanges thereof, the following construction is preferably employed:

The cross member B provided with the upwardly extending side flanges is provided at 100 the points of intersection of the downwardly extending flanges of the cross member A with shallow recesses or notches b into which the side flanges of the member A are adapted to enter, and the downwardly extending side flanges of the member A are provided with notches or recesses a extending throughout 105 the greater portion of the depth of the side flanges. By means of these cooperating notches or recesses in the vertical flanges of the two cross members, the two members can be nested or interlocked as shown in Figs. 2, 110

5 and 7, without materially decreasing the strength of these two members. The upwardly extending side flanges of the member B are so arranged that when a downwardly 5 acting weight is applied to the seat D, the upper edges of these flanges are in tension, and since these upper edges are only slightly notched by means of the depressions or notches *b*, their strength is practically unin- 10 paired. The lower portions of the downwardly extending flanges of the cross member A on the other hand are in compression when weight is placed upon the seat D, and consequently, their strength is not impaired 15 by the notches or slots extending almost throughout the length of the downwardly extending flanges for the reason that these notches are filled by the upwardly extending flanges of the member B, so that the action 20 of the downwardly extending flanges, when subjected to compression, is not in any way changed by the notches *a*.

A suitable reinforcing or compression member, such as a sleeve or short tube C' is 25 preferably placed around the reduced upper end *c* of the chair spindle C and between the horizontal flanges of the two cross members, so that the bending or deformation of the 30 cross members by the shoulder and the riveted end of the spider is prevented, when the spider is subjected to strains.

If the chair fitting is to be used in connection with a tilting back pivoted to the chair seat spider, this can be done by pivot- 35 ally mounting a pivoted member E on a part of the chair fitting, for example, by providing holes in the upwardly extending flanges of the longitudinal cross member B through which a pivot pin *e* may extend, the ends of 40 which extend through holes in the pivoted member E, these holes being preferably formed in upright flanges or parts *e'* of the pivot member E, which are connected at their front ends by means of a stop or bridge member *e*². The rear end of the pivoted member E is preferably provided with a bearing lug or projection *e*³ through which a pivot pin *f* extends, which is connected 45 with bearing lugs *f'* formed on a back sup- 50 porting member F on which the back post G of the chair back is suitably secured.

In order to hold the back post G in a substantially upright position, a spring is commonly employed which acts on the pivoted member E. In constructions heretofore employed, one or more coil springs were used for this purpose, which had to be secured to the pivot member at a considerable distance above the pivot *e* in order to obtain 55 the necessary fulcrum for offering the desired resistance to the rearward movement of the back post G. These coil springs, in addition to having the disadvantages of requiring considerable room vertically, also necessitated the use of certain relatively 60

movable parts which were noisy and caused squeaks which were difficult to eliminate, and which involved a considerable amount of friction, so that the action of the spring on the chair back was not uniform. In order to 70 avoid the objection to the use of coil springs, the following construction is preferably employed:—

A pair of spring rods or springs H is provided, the front ends of which are secured in 75 any suitable or desired manner in the ends of a yoke member I arranged adjacent adjacent to the forwardly extending part of the cross member B. The other ends of the spring wires or rods H are preferably hooked 80 under ears or lugs *h* formed on the pivoted member E and extending outwardly from opposite sides of the vertical flanges or parts *e'* of the pivoted member E, and the intermediate portions of the spring rods or members H are preferably provided with loops 85 which extend around the cross bar A of the spider. The two looped portions of the spring rods or bars are preferably so arranged that each contacts only at one point 90 on the cross member A, for example, in the construction shown, these spring bars or wires contact only on the upper rear edge or corner of the cross member A. From this construction it will be seen that the pivoted member E, in order to swing downwardly 95 about the pivot *e* must do so against the action of the spring rods or wires H, and by adjusting the yoke I at the other end of the spring rods vertically, the pressure which 100 the spring rods exert against the lugs *h* of the pivot member E may be regulated as desired. By means of this spring arrangement, all longitudinal bearings are eliminated, and consequently the squeaks resulting 105 from these bearings are also eliminated. It will be noted that swinging of the pivoted member E about its pivot produces practically no movement of the springs relatively to the lugs *h* since the lugs *h* and the 110 rear ends of the spring rods swing about pivots located in close proximity to each other. The springs arranged as described offer a smooth and uniform resistance to the rearward tilting of the chair back, since each 115 spring engages the spider at only one point so that there is no friction or binding action between the spring and any other part of the chair fitting. Also the construction described makes it possible to pivot the member E in close proximity to the seat, so that 120 the chair fitting requires considerably less material and is consequently lighter in weight, without any sacrifice of strength. The cross or bridge member *e*² is adapted to engage the cross member B to limit the extent to which the back can be swung rearwardly against the action of the spring rods H, and stop lugs *e*⁴ limit the extent to which 125 the spring rods swing the back forwardly. 130

The yoke member I is preferably adjustable vertically by any suitable means, such for example as an adjusting screw *i* having a threaded engagement with a central hole 5 in the yoke member I, the lower end of the screw *i* being provided with a head *i'* by means of which the adjusting screw can be readily turned. The upper end of the adjusting screw bears against a socket or depression formed in the cross member B. Any other means for changing the tension of the spring rods may be employed, if desired.

The back supporting member F is provided with an upwardly extending part K 15 having flanges *k* at the sides thereof between which the back post G is held, and the upright portion K is preferably provided with a longitudinal slot *k'* through which a bolt L may extend, the bolt also extending 20 through a hole in the lower portion of the back post G, and a nut *l* may be used for securing the bolt L in any desired position in the slot *k'*, and thus securing the desired vertical adjustment of the back post G. This 25 construction is particularly desirable for the reason that it eliminates the usual longitudinal slot in the back post G, which is more difficult to make than the slot *k'* in the adjusting member, and which also weakens the 30 back post.

It is also desirable to provide an adjustment whereby the back post may be moved forwardly or rearwardly with reference to the chair seat. For this purpose the back 35 supporting member F is, in the construction shown, provided with a substantially horizontal, forwardly projecting extension M at the lower portion thereof. At the front end of this extension is provided an adjusting 40 screw *m* having a head end *m'* and adapted to engage the pivot member E. A pair of springs N is preferably provided for normally holding the adjusting member F in a position in which the adjusting screw *m* engages the pivoted member E. Consequently, 45 by turning the adjusting screw, the back of the chair back may be moved forwardly or rearwardly with reference to the seat thereof. The back post adjustment described is thoroughly reliable and positive in its action, and 50 can be readily varied by merely turning the screw *m*, and without changing the position of the back post relatively to the back supporting member F.

55 I claim as my invention:—

1. A spider for chair seats including a pair of crossed members each of which has a substantially horizontal flange and a substantially vertically extending reinforcing flange, one of said members being arranged 60 with its reinforcing flange extending upwardly and the other member being arranged with its reinforcing flange extending downwardly, said downwardly extending flange being slotted to receive said upward-

ly extending flange, whereby the slot in said downwardly extending flange is closed by said upwardly extending flange and leaves the strength of said downwardly extending flange unimpaired when subjected to compression. 70

2. A spider for chair seats including a pair of crossed members each of which has a substantially horizontal flange and a substantially vertically extending reinforcing flange, one of said members being arranged 75 with its reinforcing flange extending upwardly and the other member being arranged with its reinforcing flange extending downwardly, said downwardly extending flange being slotted to receive said upwardly extending flange, and a notch in said upwardly extending flange adapted to receive a part of said downwardly extending flange, whereby said members are held against lateral displacement relatively to each other. 80

3. A spider for chair seats including a pair of crossed members of channel shaped cross section, one of said members being arranged with its flanges extending upwardly and the other member being arranged with its flanges extending downwardly, said downwardly extending flanges being slotted 85 to receive said upwardly extending flanges, whereby the strength of said downwardly extending flanges to resist compression is unimpaired. 90

4. A spider for chair seats including a pair of crossed members of channel shaped cross section, one of said members being arranged with its flanges extending upwardly and the other member being arranged with its flanges extending downwardly, said upwardly extending flanges being provided with notches to receive parts of said downwardly extending flanges. 100

5. A spider for chair seats including a pair of crossed members of channel shaped cross section, one of said members being arranged with its flanges extending upwardly and the other member being arranged with its flanges extending downwardly, alined recesses in the flanges of each member into which the flanges of the other member enter to secure said members in fixed relation to each other, and means for securing said members in their interlocked positions. 110

6. A spider for chair seats including a pair of crossed members of channel shaped cross section, one of said members being arranged with its flanges extending upwardly and the other member being arranged with its flanges extending downwardly, alined recesses in the flanges of each member into which the flanges of the other member enter to secure said members in fixed relation to each other, and a central seat-supporting spindle, the upper end of which passes through said members at the intersection thereof and secures said members together. 120

7. A fitting for chairs including a spider having a longitudinal part which is secured to the lower face of the chair seat and which extends downwardly therefrom, a transversely extending member connected with the lower portions of said longitudinal part, a rigid member which carries the chair back and the front end of which is pivoted to said longitudinal part in rear of said transverse member and adjacent to the seat, and a spring rod having a coil in the intermediate portion thereof surrounding said transversely extending member and having its rear end engaging and exerting upward pressure on said pivoted member in rear of the pivot thereof, and adjusting means at the front end of said spring rod for varying the pressure exerted by said spring rod on said pivoted member.
8. A fitting for chairs including a spider having a longitudinal part which is secured to the lower face of the chair seat and which extends downwardly therefrom, a transversely extending member connected with the lower portions of said longitudinal part, a rigid member which carries the chair back and the front end of which is pivoted to said longitudinal part in rear of said transverse member, a spring rod having a coil in the intermediate portion thereof surrounding said transversely extending member and engaging said transversely extending member at one point only, said point of contact being arranged in proximity to the pivotal connection between said spider and said pivoted member, said spring rod having its rear end engaging said pivoted member in rear of the pivot thereof and exerting upward pressure on said pivoted member, the front end of said rod extending toward the front of the chair spider, and adjusting means at the front end of said spring rod for varying the pressure exerted by said spring rod on said pivoted member.
9. A fitting for chairs and the like including a chair supporting spider having a transversely extending member, a member which carries said chair back and which is pivoted on said spider, and a spring rod arranged below said chair seat and having its front end adjustable with reference to the chair seat and extending rearwardly and engaging said transverse member at the upper rear portion thereof and bent into a coil which extends around said transverse member out of contact therewith, said coil terminating in a rearwardly extending portion and which engages said chair back carrying member.
10. A fitting for chairs and the like including a back supporting part pivoted at its front end on the chair, a member to which the back post may be secured and which is pivotally connected to the rear end of said part, a bracket extending forwardly from the lower part of said member, an adjusting screw on said bracket and adapted to engage said part for swinging said member about its pivotal connection with said part, and a spring acting on said member and said part for normally holding said adjusting screw in engagement with said part.
11. A spider for chair seats including a pair of crossed members of channel shaped cross section, one of said members being arranged with its flanges extending upwardly and the other member being arranged with its flanges extending downwardly, alined recesses in the flanges of each member into which the flanges of the other member enter to secure said members in fixed relation to each other, a central chair supporting spindle having a reduced upper end extending through said members at the intersection thereof, the upper end of said spindle being riveted against the upper of said cross members and the juncture of said reduced end with said spindle forming a shoulder on which said lower crossed member rests, and a reinforcing spacing sleeve surrounding said reduced end of said spindle and interposed between said crossed members to prevent distortion thereof when said spider is subjected to strains.
12. A spider for chair seats including a pair of crossed members of channel shaped cross section, one of said members being arranged with its flanges extending upwardly and the other member being arranged with its flanges extending downwardly, alined recesses in the flanges of each member into which the flanges of the other member enter to secure said members in fixed relation to each other, a central chair supporting spindle, the upper end of which passes through said members at the intersection thereof and which has an annular shoulder on which the lower of said crossed members rests, means on said spindle engaging the upper of said crossed members to secure said crossed members together, and a compression member arranged between said crossed members and about the portion of said spindle which extends between said crossed members to prevent deformation of said crossed members.

ROBERT K. DAWSON.
